UNITED STATES PATENT OFFICE.

JOSEPH C. CALMEYN, OF CHICAGO, ILLINOIS, ASSIGNOR OF ONE-HALF TO JAMES CARMICHAEL, OF CHICAGO, ILLINOIS.

KNOCKDOWN BOX.

1,099,422.

Specification of Letters Patent. Patented June 9, 1914.

Application filed March 15, 1911. Serial No. 614,751.

To all whom it may concern:

Be it known that I, JOSEPH C. CALMEYN, a citizen of the United States, residing at Chicago, in the county of Cook and State of Illinois, have invented certain new and useful Improvements in Knockdown Boxes, of which the following is a specification.

The present invention relates to improvements in knockdown boxes adapted for the shipment of food stuffs, vegetables, provisions and the like and aims to provide a simple, strong, durable and inexpensive device of this character which may be readily set up for use and, when emptied of its contents, easily knocked down or disassembled so that a number of the boxes may be nested or strapped together into a neat compact form for return shipment or storage.

This invention embodies various novel features of construction designed to coöperate in the accomplishment of certain objects, among which are, the provision of means whereby the sides and ends of the box are detachably locked to the bottom when the box is opened but may be detached therefrom when the box is collapsed and also novel means for engaging the top of the box with the sides and ends upon lateral sliding movement of the top.

Other objects and advantages will be apparent as the invention is better understood by reference to the following description when taken in connection with the accompanying drawings illustrating one preferred embodiment thereof.

Referring to the drawings—Figure 1 is a perspective view of a box embodying my invention. Fig. 2 is an end view thereof. Fig. 3 is a transverse sectional view through the center of the box. Fig. 4 is a detail perspective view of one of the end plates. Fig. 5 is a longitudinal sectional view of the box. Fig. 6 is a perspective view looking at the under side of the box cover. Fig. 7 is a plan view of the box with the cover removed. Fig. 8 is a detail perspective view of one of the detachable brackets; and Fig. 9 is a detail perspective of one of the cover fastening devices.

From the drawings it will be observed that the box comprises a bottom member 10, side members 11, end members 12 and a top member 13. Instead of following the practice of hinging the side and end members to the bottom member as has customarily been

done heretofore in knockdown boxes and crates of various kinds, I have found it desirable and expedient to make the side and end members detachable from the bottom member so that when the box is collapsed the various members may be packed independently of each other in a small compact space and to this end I have provided means whereby the side and end members can be readily and automatically connected with the bottom member during the assemblage of the box and can be quickly and easily detached therefrom as the box is knocked down or disassembled. The connecting means preferably comprises a plurality of plates 14 secured by screws or other similar fastening means to the bottom member each provided with a perforation 16 and a slot 17 for detachable engagement with projections 18 and 19, which I have shown in form of screws, projecting from the faces of the end members and the ends of the side members, respectively. The slot 17 with which each of the plates 14 is provided has a horizontal portion for the entrance of the projection 19 and a vertical portion adapted to prevent horizontal displacement of the projection after it has been introduced therein. The perforation 16 comprises an enlarged circular portion adapted to permit the head of the screw 18 to be passed therethrough and a shallow extension at its upper side to receive the shank of the screw and prevent the head thereof from being withdrawn from the plate.

In setting up the box the side members are first introduced in a substantially horizontal plane between the companion plates 14 on opposite ends of the bottom member so as to introduce the shanks of the projections 19 into the horizontal portions of the slots 17. The side members are then turned upwardly into position perpendicular to the bottom member, the engagement of the lower edge of the side members with the face of the bottom member during the tilting movement serving to raise the projections 19 into the vertical portions of the slots 17, thereby preventing lateral displacement of the side members. In order that the side members may not be tilted beyond their perpendicular relation to the bottom member, I provide suitable stops adapted to limit the swinging movements of the side members, the stops being shown in the present instance

as screws 20 projecting upwardly from the bottom member intermediate its length. The lower edges of the side members are preferably recessed at 21 to accommodate the screws 20 so that the stops may be located entirely within the plane of the box. An intermediate position of the side members as they are being brought from horizontal to perpendicular position is shown in dotted lines in Figs. 2 and 3. After the side members are assembled the end members may be placed in position by moving them outwardly against the plates 14 substantially in the plane indicated in dotted lines in Fig. 5 until the heads of the projections 18 are passed through the enlarged portions of the apertures 16, thereupon the end members may be tilted to perpendicular position, the lower edges of the members sliding 20 along the face of the bottom member serving to raise the projections 18 into the shallow extensions of the apertures 16 whereby the end members are locked against lateral displacement. In order to facilitate the 25 swinging movement of the end members into position, their lower outer corners are preferably rounded off as indicated at 22 so that they will the more readily slide along the face of the bottom member.

30 In order to rigidly secure the side and end members together after they have been assembled, to prevent collapsing of the box and also to afford greater strength and rigidity to the structure as a whole, I have 35 provided the inner face of each of the end and side members adjacent its end with screws or other similar projections 23 which are adapted to be detachably engaged by strengthening brackets 24. As shown in 40 Fig. 8 each of these brackets is of angle formation and is provided with downwardly opening slots 25 adapted to slide over the shanks of the projections 23 to securely fasten the end and side members together.

45 It will be evident that the brackets can be easily attached when the box is set up and readily removed when it is desired to take the box down.

The cover member 13 which is detachable 50 from the rest of the box is designed to be secured to the side and end members by a limited lateral movement. From Fig. 6 it will be observed that a pair of hook shaped members 26 is secured to the bottom face of 55 the cover adjacent one edge thereof with the tongues 27 projecting inwardly and that the member 28 is secured adjacent the opposite edge of the cover with its tongue 29 projecting in the same direction as the tongues 27. One of the side members is 60 provided with recesses 30 adapted to receive the tongues 27 while the other side member is provided with a similar recess positioned to receive the tongue 29. When 65 the cover is resting upon the upper edges

of the open box it will be evident that limited lateral sliding movement will bring the tongues 27 and 29 into their respective recesses. Each of the end members is equipped with a plate 32 having one end 33 thereof bent outwardly, said portion being provided with a slot 34. The lower face of the cover is also equipped with similar plates 32 positioned to slidably engage with the plates upon the end members when the cover is slid into closed position. It will thus be seen that the cover when in position is lockingly engaged with both side members and both end members, thereby not only insuring a tight fit of the cover 80 but also adding strength and rigidity to the box.

It is, of course, desirable that the cover be locked in some manner in position after it has been applied, and in Fig. 3 I have 85 shown one simple type of locking means. In this instance a hole is drilled through the cover into the upper edge of the side member and the tongue 29 is perforated to receive a pin 35 inserted through the cover 90 and tongue and into the side member. Other locking means may be employed if preferred, for instance, the tongue 29 might be extended entirely through the side member and a padlock or key might be engaged in the perforation provided in the portion of the tongue extending outside the box. Preferably, however, the locking means should be disposed entirely within the plane of the box so as to leave no projecting portions 100 which might be liable to be broken off.

While I have shown and described a preferred embodiment of my invention it will be obvious that various changes in the size, shape and proportion of the various parts 105 may be resorted to and if preferred the sides, ends and top may be made of slats or similar open work construction thereby producing an open crate adapted to accommodate poultry, etc., and that other mechanical 110 changes may be resorted to without departing from the spirit or sacrificing any of the advantages of the invention.

I claim:

1. In a knockdown box, the combination 115 of a bottom member, end members, side members, perforated plates carried by said bottom member, and projections arranged on said side and end members in position to engage with said plates and lock the side 120 and end members to the bottom member when in perpendicular relation and permit the side and end members to be detached from the bottom member when tilted from said perpendicular position.

2. A knockdown box comprising end, side and bottom members, and means for securing the said members together, the said means comprising a plate permanently and rigidly fixed to one of said members and 130

provided with an aperture and a slot for detachable engagement with the other members, the said engagement rigidly connecting the said side, end and bottom members 5 upon movement of the said members to which the said plate is detachably engaged.

3. A knockdown box comprising bottom, end and side members, and a plate permanently and rigidly secured to the bottom 10 member, said plate being provided with an aperture and a slot, and the end and side members being equipped with suitable projections to be inserted in the said aperture and slot and engaged therewith, the said 15 engagement being completed by movement of the side and end members into upright position.

4. In a knockdown box, the combination of bottom, end and side members, common 20 means permanently and rigidly secured to said bottom member for detachably connecting said end and side members to the bottom member when the said end and side members are inclined to the bottom member 25 and for locking the said members one to the other upon movement of the end and side members to a perpendicular position relatively to the bottom member, and detachable means for rigidly securing the said end and 30 side members together at their tops.

5. A knockdown box comprising a bottom member, a plurality of plates secured upon each end of said bottom member and 35 each of said plates being provided with a perforation and a slot, side members, studs projecting from the ends thereof and adapted to be lockingly engaged in said slots when the side members are tilted into verti-

cal position, end members equipped with projecting studs adapted to lockingly engage in said perforations when the end 40 members are tilted into vertical position, and a cover provided with means whereby said cover is locked to both of said side members and both of said end members 45 upon sliding movement transversely of the box.

6. In a knockdown box, the combination of bottom, end and side walls, an upwardly disposed plate secured to an end of the bottom wall and having a slot and an aperture 50 formed therein, a projection upon the end wall, and a projection upon the end of a side wall adapted to be engaged respectively with the aperture and slot of the plate when 55 the walls are in tilted position and to firmly lock the walls together when in vertical position.

7. In a knockdown box, the combination of bottom, end and side walls, a plurality of 60 upwardly extending plates secured to the ends of the bottom wall, each provided with an aperture and a slot, projections upon the end walls to engage in the said apertures, and projections upon the ends of the side 65 walls to engage in the said slots, said projections being arranged to engage with the apertures and slots when the side and end walls are in tilted position and to secure these walls in position when the same are 70 vertically disposed.
